UNITED STATES PATENT OFFICE.

EDMUND LAND, OF JACKSONVILLE, FLORIDA.

CABLE-PROTECTOR.

1,172,466.

Specification of Letters Patent. Patented Feb. 22, 1916.

Application filed May 6, 1914. Serial No. 836,722.

To all whom it may concern:

Be it known that I, EDMUND LAND, a citizen of the United States, residing at Jacksonville, in the county of Duval, State of Florida, have invented certain new and useful Improvements in Cable-Protectors, of which the following is a specification.

The present invention relates to devices for protecting cables of various sorts and especially cables which carry electric light, telephone, or telegraph, wires, and which are often strung through trees and in other places where they are subjected to the abrading action of objects with which they come in contact.

It has been the practice heretofore to protect such a cable at the point of possible abrasion, by placing strips of wood around the cable and holding them in place by binding wires. In following this practice, the workman is compelled to ascend to the point where the cable is to be protected and there handle three or more strips of material and bind them in place while he himself hangs on to such support as he can. Because of the difficulty of access, it is often a difficult job to apply the protection to the cable according to this old practice.

The object of my invention is to provide a cable protector, or cable protecting fabric, which may be applied with greater facility and with less expenditure of time and energy than is possible under the old practice. To this end, I provide a fabric which is made up of a number of strips of wood or other rigid protecting material arranged side by side and flexibly secured together with wire or other suitable material and provided with loops or extensions of wire, or its equivalent, in association with each strip. This fabric can be made up in rolls, much the same as wire fencing, and cut off as needed.

The full character of my invention will be more fully understood upon reference to the following detailed description taken in connection with the accompanying drawing, and the scope of the invention will be particularly pointed out in the appended claims.

In the drawing, Figure 1 is a plan view of a portion of a protector fabric constructed in accordance with the present invention; Fig. 2 is a vertical section of one of the strips, the plane of section being indi-

cated by the line 2-2 of Fig. 1; Fig. 3 is a side elevation of one of the strips; Fig. 4 is an end elevation of the fabric shown in Fig. 1; Fig. 5 is a transverse section of the same taken on a plane indicated by the line 5-5 of Fig. 1; Fig. 6 is an end elevation similar to Fig. 5 illustrating modifications of the structure of the preceding figures; and Figs. 7 and 8 are a perspective view and a transverse section, respectively, of still further modifications. Throughout these views like characters refer to like parts.

Referring to the drawing in detail, 10 designates strips of wood or other rigid material suitable for the protection of the cable. These strips may be of varying widths, thicknesses and lengths. They are positioned side by side, preferably with intervening spaces as illustrated. They are fastened together by pairs of wires 11 and 12 which are arranged at intervals lengthwise of the strips. Any desired number of pairs of wires may be employed, depending largely upon the length of the strips. These wires 11 and 12 are secured together so as to hold the strips 10 in position. In the form of the invention illustrated in Figs. 1 to 5, inclusive, the wire 11 is a straight wire extending through transverse holes in the strips 10 and the wire 12 is of considerably greater length and is wrapped around the wire 11 in the spaces between adjacent strips. Besides securing the strips 10 together and holding them in place, the wires 11 and 12 are arranged to provide one or more binding pieces for each strip. In the form of the invention illustrated in Figs. 1 to 5, inclusive, the binding pieces are formed by providing the wire 12 with a loop 13 at each of the intervening spaces. As shown, the wire 12 passes over the outside of the strip 10.

In making up a protector from this fabric, the lineman or other user, knowing the diameter of the cable which he wishes to protect, decides on the number of strips 10 which he will need for the particular cable. He then cuts the loop 13 and the wire 12 of each pair of wires at that space which will give him the desired number of strips. In other words, he cuts off the amount of material necessary for the particular protector which he is about to fashion. In bringing this material to the cable, he has but a sin-

gle article to handle and therefore can more readily manipulate it so as to position the strips around the cable, than in the old practice where there were several unconnected strips. When the strips are in position, the portions of the severed loops upon the first and last strips, may be drawn up and twisted together so as to draw all the strips into close engagement with the cable and thus securely bind all the parts together. If desired, the other loops may also be twisted together or bent down out of the way or otherwise disposed of.

It will be noted that in the form of invention illustrated in Figs. 1 to 5, inclusive, the ends of the wires forming loops 13 at the point where they are wrapped around the wire 11, are close together. Obviously these may be separated, as are the corresponding branches of the loop, as in Figs. 7 and 8. With this separation it is easier to sever the wire upon which the loop is located.

In the form of the invention illustrated in Fig. 6, the wires 14 and 15 correspond to the wires 11 and 12 of Fig. 1. In this instance the wire 14 extends through holes in the strips 10 just as does wire 11. The latter strips, however, have a sheet of fabric 16 positioned on their upper side, through which the wire 15 is passed to firmly secure the fabric to the strips. This fabric may be of any desired material, depending upon the use to which the protector is to be put. In some instances it may be desirable to use an insulating fabric, in others a waterproof fabric, and in other instances materials having other functions. In this form of the invention, the wire 15 may be looped as at 17, 17 and left as loops, or the loops may be severed so as to leave the ends 18. In either event, when it comes to binding the protector on the cable, ends must be used. In the first case these ends are provided by severing the appropriate loops at the time of making up the protector. In the latter case all the loops are cut at the time of manufacture so that when the time for installing arrives only the straight wire 14 has to be cut.

It is obvious that the strips may be flexibly united by various means and that where wire is used the strips may be bound together by arranging the wires in different ways. It is also obvious that the piece of flexible binding material associated with each strip may be provided in different ways. In the examples given, these binding pieces are in all instances provided by severed loops. But these are merely illustrative. It will also be apparent that the loops or ends of wire which constitute the flexible binding pieces may be given any desired length, provided they are made of sufficient length to permit the binding pieces

which are to be used in binding, to be brought into proper fastening engagement after the parts have been firmly drawn up around and against the cable.

Fig. 7 illustrates an arrangement of binding wires and strips in which the strips 10 are provided with transverse upper grooves 19 and similar lower grooves 20. The wire 21 extends through the grooves 19, and the wire 22 through the grooves 20. In this instance the loops 23 are formed in the wire 22.

In Fig. 8 we have an instance where the wire 24 rests in a groove 25 in the upper face of each of the strips 10, and the wire 26 is used to form the loop 27 and to pass through the sheet of fabric 16 to bind the latter upon the strips 10. The latter wire is also wrapped around the wire 24 at the spaces between adjacent strips, as in the other figures.

These modifications show that there are many ways in which the strips may be secured together, whether they be used alone, or with fabric, and that there are many ways in which the binding pieces themselves may be fashioned. I, therefore, do not wish to be limited to the specific forms of the invention herein disclosed, because there are many changes and alterations which may be made upon such forms without departing from the spirit and scope of my invention. I, therefore, aim to cover all such alterations and modifications by the terms of the appended claims.

What I claim as new and desire to secure by Letters Patent of the United States is:

1. A cable protecting fabric comprising strips of rigid protecting material positioned side by side, flexible connections between adjacent strips, and a piece of flexible binding material associated with each strip and of such length that adjacent pieces may be fastened together to secure adjacent strips together independently of and alternative to the corresponding flexible connections.

2. A cable protecting fabric comprising strips of wood, pairs of wires extending transversely of said strips, each pair being twisted together so as to secure said strips side by side with intervening spaces, and each pair being formed with elongated portions between adjacent strips to serve as alternative binding means when the wire between the corresponding adjacent strips is severed.

3. A cable protecting fabric comprising strips of rigid protecting material positioned side by side, a sheet of fabric overlying said strips and firmly secured thereto, and a piece of flexible binding material associated with each strip and of such length that adjacent ones of said pieces may be united to secure adjacent strips together in-

dependently of and alternative to the connection formed by that portion of said fabric sheet which flexibly unites them.

4. A cable protecting fabric comprising strips of wood positioned side by side, a sheet of fabric overlying said pieces, and pairs of wires extending transversely of said strips at intervals along their length, each pair being secured together to secure 10 said strips in position and to secure said sheet to said strips, and each pair being formed with elongated binding portions.

5. A cable protecting fabric comprising strips of rigid protecting material positioned side by side, flexible connections between adjacent strips, and pieces of flexible binding material associated with adjacent ones of said flexibly connected strips and long enough to be fastened together to secure 15 adjacent strips together in case the said flexible connection between said adjacent strips be severed.

6. A cable protecting fabric comprising strips of wood positioned side by side with 20 intervening spaces, wires extending transversely of said strips and flexibly securing certain of said strips together, and wire binding pieces associated with adjacent ones 25

of said flexibly connected strips for fastening and securing said adjacent strips together in case the wire or wires constituting the said flexible connection between said adjacent strips be severed. 30

7. A cable protecting fabric comprising strips of wood positioned side by side with intervening spaces, a pair of wires extending transversely of said strips and twisted together in said spaces to connect and firmly hold said strips, and elongated loops formed of said wire at certain of said spaces to provide in each instance a connection between the strips on either side of said space alternative to the normal connection between said strips formed by said wires. 35

8. A cable protecting fabric comprising adjacent flexibly connected strips positioned side by side, and an alternative connecting means for securing said strips in position whenever their flexible connection to each other is destroyed. 40

In witness whereof I hereunto subscribe my name this 2nd day of May, A. D. 1914.

EDMUND LAND.
